UNITED STATES PATENT OFFICE.

DOUGLAS E. BONNER, OF NEW YORK, N. Y.

COLLAPSIBLE HOOD.

1,184,312.

Specification of Letters Patent.

Patented May 23, 1916.

Application filed July 14, 1913. Serial No. 778,820.

To all whom it may concern:

Be it known that I, DOUGLAS E. BONNER, a citizen of the United States, and a resident of New York city, county and State of 5 New York, have invented certain new and useful Improvements in Collapsible Hoods, of which the following is a specification.

My invention relates to hoods, tops or covers particularly adapted for use on vehicles of any type, on small boats and as awnings of any description and relates more specifically to that type of hood, top or cover which may be raised and collapsed or folded at will.

15 My improvement has for its object to provide a construction which may be readily and easily raised to its intended operative position and in which the various parts will properly adjust themselves to the desired 20 folded position without interference when the hood, top or cover is collapsed.

Other objects of my invention will appear in the description hereinafter and the features of novelty will be pointed out in the 25 appended claims.

Reference is to be had to the accompanying drawings in which—

Figure 1 is a view of my improved hood, top or cover in its extended or raised position with parts in section; Figs. 2 and 3 illustrate the same in successive stages during the folding operation; Fig. 4 is an enlarged detail view with portions of the parts in the same position as in Fig. 1, and Fig. 5 35 is a detail view of certain other parts.

In the drawings the hood, top or cover as shown comprises the main bow 10 and rear bow 11 both pivotally connected for instance at 12 with the object to be covered which as 40 before stated may be a vehicle, small boat or the like. The construction may also include an intermediate rear bow 13 pivotally connected at 14 with the rear bow 11, it being understood that in some cases this intermediate bow 13 may be pivoted to bow 10 or 45 may be omitted entirely. An articulated front or peak bow 15 is pivoted at 16 to the main bow 10 and comprises a front section 17 pivotally connected with rods 18 prefer- 50 ably though not necessarily by means of rule or break joints 19. The customary covering material 20 is secured to the bows 10, 11, 13 and 15 and to the object, such as a vehicle body in any well known manner and so as

to be stretched and supported over said object when the hood etc. is raised. In the construction as shown an auxiliary bow 21 has its opposite ends pivotally connected at 22 with the rods 18 and is also preferably connected with the covering material 20. In 60 the unfolded or raised position of the hood, the peak or front bow is intended to extend in front of the main bow 10 substantially in a horizontal direction over the vehicle or other object to be covered and is prevented 65 from the possibility of accidentally collapsing or folding by means of a brace 23 acting in conjunction with the usual holding straps or other means. This brace 23 has one end pivotally connected at 24 with the main bow 70 10 and at its other end is preferably provided with a slot 25 through which the pivot 26 for connecting said brace with the front section 17 of the peak bow 15 extends.

As shown in Fig. 1 the auxiliary bow 21, 75 in the raised condition of the top is inclined relatively to the peak bow 15 and is maintained in this position by means of the covering material 20 or an articulated link 27 pivotally connected at 28 and 29 respectively 80 with the brace 23 and auxiliary bow 21 and having its sections pivotally connected together at 30. This link 27 in addition to its other functions also prevents interference 85 between the auxiliary and peak bows during the collapsing of the top and insures a proper folding thereof. It will be obvious that the various pivots are so arranged that the hood or top when raised will assume substantially the position shown in Fig. 1 of 90 the drawings and also in such a manner that when the hood or top is closed the bows 10, 15 and 21 will come together and be substantially parallel. In the arrangement of pivots best suited to secure the practical and desired extended position of the top, it is sometimes found that at some point during the closing or folding of the top the ends of the bows 15 and 21 come into contact and bind 95 thus interfering with the further closing of 100 the top and also injuring the covering material 20 by pinching it between the ends of said bows. With the articulated and flexible link 27 these dangers and objections are overcome for the reason that as the parts 105 assume the position shown in Fig. 2, the link 27 having become flexed will move the end of the bow 21 away from the end of the bow

15 and thus prevent any interference between the same as well as any chafing or pinching of the covering material 20. The said flexible link 27 by being flexed more or less in the extended position of the top also permits the auxiliary bow to be arranged at different angles as will be readily apparent from an inspection of Fig. 1 of the drawings. In addition to this it is also possible 10 to overcome and nullify the effects of inaccurate drilling or positioning of the various pivot holes by means of said flexible link 27. In other words the combined distance between the pivots 22, 29, 28 and 24 is made 15 slightly greater than the distance between the pivots 24, 16 and 22 so that when the bows 15, 21 and 10 are adjacent to each other in the folded position of the top and the drilling is accurate the said link 27 will 20 be slightly flexed. If however through inaccurate drilling the combined distance between the pivots 22, 29, 28 and 24 is too short, the said link 27 will straighten out and compensate for such inaccuracies while if the 25 said combined distance, through inaccurate drilling is too great the said link will be further flexed to compensate for these latter inaccuracies. In either case the proper folding of the bows 15, 21 and 10 is absolutely assured.

To still further guarantee the proper folding of the top and particularly the front portion thereof, I prefer to connect the brace 23 with the peak bow 15 by means of the 30 slot and pivot connection 25, 26 heretofore referred to. I arrange this connection so that the pivot 26 is at the outer or lower end of the slot 25 when the top is extended and at or near the upper or inner end thereof 35 when the bows 15, 21, and 10 are brought together or folded. In the arrangement as shown the pivot 16 is in front of pivot 24, assuming the top to be raised, or in other words is advanced beyond the longitudinal 40 median line of the bow 10 which passes through the pivot 24. Consequently at some point during the closing operation the pivot 26 will come into line with the pivots 16 and 24 or in other words a position indicated by 45 a broken line in Fig. 2 and which might be termed the dead center is reached. Ordinarily any further closing or folding of the forward section of the top would distort the members or otherwise would necessitate 50 either a shortening of the brace 23, or a reduction of the distance between the pivots 26 and 19 or an increase of the distance between 16 and 19 or between 16 and 24. With 55 the present construction these disadvantages 60 are overcome and the front section of the top may be completely folded owing to the fact that a movement beyond the above mentioned dead center position will cause the pivot 26 to move lengthwise of the slot 25 65 and relatively to the brace 23. The particu-

lar slot and pivot arrangement also permits the forward section of the top to be freely extended or unfolded by means of a slight manual effort applied only at some point at the top of the bow 15. Thus after the rear section of the top has been raised to the position shown in Fig. 3 of the drawings a simple forward pressure on the upper portion of the bow 15 will move the bows 15, and 21, and brace 23 from their folded position to or slightly beyond the dead center position hereinbefore mentioned or in other words to substantially the position shown in Fig. 2 of the drawings. In some cases the weight of the bow 15 alone will cause the 80 forward section of the top to drop to said position by gravity. In either case by pressing forward on the bow 15 as described, the rods 18 and brace 23 will be swung on the respective pivots 16 and 24 and will bring 85 the said forward section of said top to the unfolded or extended position shown in Fig. 1. That is to say with the construction shown and described a forward manual effort, exerted on the bow 15 with only one 90 hand will be sufficient to raise the forward section of the top, the parts adjusting themselves automatically throughout such movement. If this is attempted with structures in which the pin and slot connection between 95 the brace and peak bow is not present and in which the various members when completely folded are back of the dead center position, it may be found that the leverages exerted are such as to cause said forward effort or pressure on the upper part of the peak bow to more closely fold the said members composing the forward section of the top, instead of bringing said section to its extended position. The pivot and slot construction also overcomes inaccuracies in positioning the pivot holes by properly dimensioning the slot.

With the present invention, when the top is completely folded the pivot 26 is located 110 in the upper portion of the slot 25 while the link 27 is slightly flexed. This makes it possible to slightly raise the section 17 of the bow 15 independently of the remaining elements of the top and also permits a limited 115 relative movement of the bow 21 an arrangement which presents the following important advantages: First it permits the bow 15 or bow 21 to be easily raised to a limited extent without the necessity for raising heavy 120 additional parts, so that any covering material which as frequently happens in the folding operation happens to fall outside of the bows can be conveniently and properly stuffed between the front bow and the auxiliary bow or between the auxiliary bow and the next adjacent bow. Secondly if it 125 should occur that more covering material than is properly intended to, fell inward between the above mentioned bows when the 130

same are folded a positive closing of said bows in arrangements other than the present one would squeeze and probably cut or otherwise injure said material. With the 5 constructions herein shown and described the two bows 15 and 21 in a contingency such as above would stop closing at a point where the excess of material between them arrested such closing movement. The said 10 material caught between these bows would thus only be subjected to the weight thereof and not to a leverage and shear like action or pressure as would otherwise be the case. The operator noting that the bows had not 15 fully closed would immediately re-arrange this covering material properly an operation which may be performed with ease and comfort when the bows are arranged to move independently as described. The said slot 20 and pivot arrangement will also prevent the brace 23 from being bent should the peak bow and auxiliary bows be raised together or become accidentally caught together. The 25 illustrated construction or its equivalent also corrects inaccuracies in the drilling of the pivot holes when the pivot is arranged to assume a position near the center of the slot as the frame of the hood is folded. The slot 25 has the further advantage that in 30 case it should be desired, it permits the main bow to be positioned vertically or inclined toward the rear in the raised position of the top without affecting or destroying the most practical arrangement of the parts necessary 35 to secure the proper folding and raising of said top. With the main bow positioned as suggested, an ordinary pivotal connection at 26, with the parts of a given top proportioned and arranged to produce the desired 40 operations, would bring the pivots 26 and 19 so close together that the necessary clearance to provide for the proper operation of the top would not be obtained and said top in consequence would not work properly. 45 In other words with the present arrangement the pivot 26 may be located at distances from the pivots 19 and 24 which are greater than they normally would be, the slot 25 serving to permit said pivot 26 to 50 change its position as is necessary to secure the proper operation of the top. It will be obvious that the elongated slot 25 as illustrated may be replaced by a hole of larger diameter than the pivot pin 26 or by other 55 equivalent arrangements which permit a free limited movement between the brace and the bows with which it is connected.

In order to still further prevent the covering material from being pinched between the bows of the forward section of the top when in a folded or collapsed condition I prefer to provide suitable retaining devices for fixing the bows against movement in said folded position. In the form illustrated these devices comprise eyelets 31 lo-

cated on the main bow 10 at opposite sides and co-operating pins 32 similarly located on the rods 18, it being understood, that the arrangement may be reversed if this should be found advisable, the eyelets or sockets 31 70 in such case being on the rods 18 and the pins 32 being on the bow 10. In either case when the top is folded or collapsed the pins 32 may be introduced into the eyelets 31 and will thus secure the bows in folded position 75 and will prevent the outer portions thereof from pressing upon or engaging each other and thus pinching or clamping the material 20 at these points. The pins and eyelets represent only an example of such devices 80 and may be replaced by equivalent means adapted to accomplish the same purpose. The material of which the bows are constructed usually has a tendency to cause the legs or side members thereof to spread apart, 85 or in other words is resilient in a direction transverse to the length of said side members, which tendency or resiliency is used in the present invention to maintain the pins and eyelets in co-operative engagement with 90 each other, it being understood that the pins and eyelets or sockets are positioned relatively to each other to secure this result.

In tops of the kind to which the present invention relates, should the covering material or strainers stretch from use and it is attempted to take up this stretch by pulling on the usual retaining straps a considerable bending force may be exerted on the tubing or the like composing the bows and other 100 parts. To overcome this strain and to do away with the injurious effects thereof I preferably use strong strainer webbing between the bows and apply it with the joints 19 not fully closed or in other words open 105 to the extent that the stretch in the covering material or webbing is not sufficient to close said joints. In this manner the bending force is converted into a compression strain on the tubing or the like when the slack is 110 taken up.

It will of course be understood that in the proposed construction the brace 23 and the link 27 may be duplicated on both sides of the top although in some cases this may not 115 be found necessary. In addition the slot 25 may be located at the opposite end of the brace 23 instead of as shown or in some cases slots may be provided at both ends and any other type of link capable of being 120 flexed may be substituted for the link 27.

Various changes in the specific form shown and described may be made within the scope of the claims without departing from the spirit of my invention. 125

I claim:

1. In a collapsible hood, a main bow, a peak bow movably connected therewith, an auxiliary bow movably connected with said peak bow, a brace movably connected with 130

said main bow and said peak bow and means connecting said brace with said auxiliary bow and capable of being flexed.

2. In a collapsible hood, a main bow, an articulated peak bow pivotally connected therewith, an auxiliary bow pivotally connected with said peak bow, a brace pivotally connected with said main bow and said peak bow and an articulated link connected with 10 said brace and said auxiliary bow.

3. In a collapsible hood, a main bow, rods pivotally connected therewith, a bow pivotally connected with said rods, an auxiliary bow pivotally connected with said rods, a brace pivotally connected with said main bow at a point above the pivoted connection of said rods and pivotally connected with said peak bow at a point between the pivot joints and the outer portion of said peak bow, and an articulated link pivotally connected with said brace and said auxiliary bows at points intermediate of the ends thereof.

4. In a folding cover the combination of 25 members comprising two bows, a plurality of bars and pivotal connections between each of said bows and said bars, one of said connections comprising an opening in one member and a projection on another member to which it is connected, said opening being 30 larger than said projection and arranged so that the folding of the cover causes the projection to slide in the opening and change its position relative thereto.

5. In a collapsible hood, a bow, an articulated bow pivotally connected therewith, a brace substantially inflexible throughout its length, said brace being pivotally connected at one end to said first named bow and

having a slot near its other end and a pivot 40 pin movable in said slot for connecting the slotted end with said articulated bow.

6. In a collapsible hood, a main bow, an articulated peak bow pivotally connected therewith, a brace pivotally connected with 45 said main bow at one end and having a slot near its other end, a pivot pin movable in said slot for connecting said other end of said brace with said peak bow, an auxiliary bow pivotally connected with said peak bow 50 and an articulated link pivotally connected with said auxiliary bow and said brace.

7. In a collapsible hood, a main bow, a peak bow pivotally connected therewith and provided with side members having a tendency 55 to spread apart and coöoperating pins and sockets on said main bow and peak bow respectively for securing said bows together when the hood is collapsed, said pins and sockets being maintained in coöperative engagement by the said spreading tendency of said side members.

8. In a collapsible hood, a main bow, a front bow connected with said main bow, an auxiliary bow connected with said front bow, a brace movably connected with said main bow and said front bow and a member connected with said auxiliary bow and with said brace and arranged to permit the 60 points of connection to approach each other. 70

In testimony whereof I have hereunto set my hand in the presence of two subscribing witnesses.

DOUGLAS E. BONNER.
